Inventor:

Charles M. Gilbert

United States Patent Office.

CHARLES M. GILBERT, OF PHILADELPHIA, PENNSYLVANIA.

Letters Patent No. 82,305, dated September 22, 1868.

IMPROVED BEDSTEAD-FASTENING.

The Schedule referred to in these Letters Patent and making part of the same.

TO ALL WHOM IT MAY CONCERN:

Be it known that I, CHARLES M. GILBERT, of Philadelphia, in the county of Philadelphia, in the State of Pennsylvania, have invented a new and improved Bedstead-Fastening; and I do hereby declare that the following is a full and exact description thereof, reference being had to the accompanying drawings, and the letters of reference marked thereon.

The nature of my invention consists of a movable bolt, with a T-head, and a slot or groove in which a key or wedge is to work on a line with the T-head, and a spring so placed as to allow the bolt to recede, or cause it to advance so as to be easily adjusted in the post as the key is pressed down or drawn up, the key having on the small end a flange to keep it from being detached from the bolt, the head of the bolt being connected with a tube or barrel, in the head of which is an opening to correspond with the head of the bolt, the tube or barrel aforesaid being of metal, and screwed into the post of the bedstead; then, as the key or wedge is pressed down, compressing the spring, it causes the bolt to recede, drawing with it the tube or barrel, and so closing up the joint or fastening of post and rail.

To enable others skilled in the art to make and use my invention, I will now proceed to describe its construction and operation.

I first prepare a bolt of iron of sufficient size, shaped as in Figure 1, in plan annexed, also an iron key or wedge, as in Figure 2, and an ordinary wire spring, Figure 3. I then take the bed-rail, Figure 4, and make two openings in it: in the end, one marked A, to receive the spring 3 and the bolt 1; the other, a transverse opening marked B, made in the side of the bed-rail 4, to receive the key 2. The bolt 1 contains a slot or groove marked D, whose perpendicular side bears the form of an inclined plane. Having inserted the spring 3 and the bolt 1 into the end-opening A, leaving the head C to project, and pressing down the bolt 1 upon the spring 3, until the slot or groove D comes opposite the opening B, I insert into this slot D the key 2, and push it, 2, into the said slot until it, the key, passes the opening A, thus holding the bolt 1, the key 2, and the spring 3 in their positions.

I next prepare an iron tube or barrel, marked 5, whose inside diameter is sufficient to allow the head C to turn freely in it, and whose head has an opening, marked E, of a shape corresponding to the shape of the bolt's head C, the outside of the said tube or barrel forming a screw. This tube or barrel, I screw firmly into the bed-post, marked 6, with the opening E transverse the post 6.

To bring the parts together, (the bolt, key, and wedge being in their positions, as described above in the paragraph next before the last,) I raise the key 2, thereby turning the bolt 1 until the T-head C is turned to a position which allows it to enter the opening E in the head of the tube or barrel 5, then bringing the key or wedge 2 to its first position, thereby turning the bolt 1 so that the flanges of its T-head C act as a guard to prevent the bolt 1 from passing out of the tube 5, through the opening E. I force the said wedge 2 further through the slot D. The inclined plane of the wedge 2, riding up the inclined plane of the perpendicular face of the slot D, causes the bolt 1 to recede deeper into the longitudinal opening A, thereby drawing up the post 6 to the rail 4, closing the joint and making it tight.

What I claim as my invention, and desire to secure by Letters Patent, is—

The combination of a key or wedge, 2, with the bolt 1, tube or barrel 5, spring 3, slotted rail 4, and post 6, as hereinabove described.
